UNITED STATES PATENT OFFICE.

EDWARD WYLDE, OF NEW YORK, N. Y., AND CHARLES SCHENCK, OF CHICAGO, ILLINOIS, ASSIGNEES TO ELEVATOR SUPPLY & REPAIR COMPANY, A CORPORATION OF ILLINOIS.

DOOR-CONTROLLING DEVICE.

1,105,053.

Specification of Letters Patent. Patented July 28, 1914.

Application filed June 20, 1913. Serial No. 774,793.

To all whom it may concern:

Be it known that we, EDWARD WYLDE and CHARLES SCHENCK, citizens of the United States, residing, respectively, at New York city, New York, and Chicago, Illinois, have invented certain new and useful Improvements in Door-Controlling Devices, of which the following is a clear, full, and exact description.

- 10 This invention relates to passenger elevators. In operating high-speed elevators it is desirable to safeguard the passengers against injury and also to save as much time as possible at the floors. Elevator doors are frequently provided with safety attachments intended to prevent the starting of the car until the door is closed. Such devices are valuable but necessitate a loss of time.
- 20 One of the objects of the present invention is to provide a safety device which will give great safety but which will result in saving time at the floors.

Our invention will be set forth in the claims.

In the preferred embodiment of our invention shown in the drawings, Figure 1 is a side elevation of a portion of the mechanism; Fig. 2 is a diagrammatic view of a preferred form of circuit which may be used when the door-controlling construction is combined with an elevator; Fig. 3 is a detail view of the dash-pot; Fig. 4 is a detail, and Figs. 5, 6 and 7 are modifications.

35 1 is a door or gate which, in the present embodiment, is horizontally slideable and is located, for example at one of the floors and allows access to the elevator 2 moving up and down in the well or hatchway of a building.

In the embodiment shown in the drawings, we have provided an automatic closing means for the door which, as illustrated, comprises a toggle consisting of levers 3 and 4 pivoted together at 5. Lever 3 is pivoted on a stationary pivot 3^a, and lever 4 is pivoted to the door at 6. Pivoted to the lateral extension 7 of the lever 4, is a link 8, which is also pivoted to a lever 9, which lever is pivoted on a fixed stud 10 carried by the door. It will be obvious that when the door is open, as illustrated in dotted lines, the movement of the toggle will cause the door to close, and conversely the movement of lever 9 toward the right will

break the toggle and open the door. The toggle and levers described may therefore be considered to be either a means for opening the door, or a means for closing.

In order to prevent an unauthorized opening movement of the door when the same has been partially closed, we have provided two parts freely movable past each other during the closing movement, but adapted automatically to engage on a reverse movement. In the preferred embodiment shown in Fig. 1 of the drawings, one of these parts is a grooved wheel 11 normally fixed on the stud 10 by the lock-nuts 12 and 13, which also allow the wheel to be adjusted if desired. The other part of the locking device is, in this embodiment, a cam 14 pivoted at 15 to the lever 9. Connected to this cam is a sliding rod 16 carrying coil spring 17, which normally presses the rod and cam toward the wheel. 18 is one means of moving the cam which, in the present embodiment, is a handle. It will be obvious that when the door is moving to the left in its closing movement, the grooved wheel 11 and the cam 14 will move freely past each other (except of course for the slight friction between the two, which is inconsiderable), but at an intermediate point in the travel of the door the cam will pass the point 20^a and then any attempted movement of the door in the reverse direction will cause the V-shaped portion of the cam to engage the groove in the wheel and lock the two together, thereby preventing the movement of the door in its opening direction.

In Fig. 5 we have shown a modification of this device, in which the lever 9 carries on its end a freely pivoted cam 20^a which, as the lever is moved in one direction, freely passes across the stationary surface 21. As the door is opened the lever is thrown across until the cam 20^a rides entirely off from the surface 21; and as the door is closed it rides back onto the surface, as indicated in dotted lines. In such position if the door is given a reverse movement in the opening direction, the cam 20^a will bite against the surface 21 and prevent the reverse movement of the door. It will be observed that in both of these locking constructions illustrated, there are two parts which are freely movable past each other during the closing movement of the door, but adapted auto-

matically to engage on an attempted reverse movement. Therefore if the elevator operator does not completely close the door, it cannot be opened from the outside of the shaft sufficiently to allow a person to pass through.

In order to automatically close the door, we have provided a spring-pressed dash-pot 22, the piston of which is connected to the lever 3 of the toggle, so that when the operator releases the handle 18 after having opened the door, the force of the spring 22^a will cause the toggle to shut and force the door to its closed position, as illustrated in Fig. 1. The toggle slightly passes the dead center in order to lock the door closed and is stopped from further movement by any suitable construction, such as a pin 23 on link 3, which engages a slot 24 on the link 4. In order to cushion the closing movement, the piston 25 fits closely in the dash-pot casing and forces the air out of a restricted opening 26, thereby giving a well known cushioning effect, which may be varied as desired by a suitable valve 27.

In the operation of high speed elevators in a building, it is important to save all the time possible, and if an operator cannot start his car until the door is entirely closed, much time is lost. It is therefore desirable to prevent the starting of the car until the door is partially closed, but to permit the car to be started before the door is entirely shut. We have provided an electric switch controlled by the door-operating mechanism and which prevents the starting of the elevator until a predetermined point in the closing movement of the door is reached. Such a switch is illustrated, for example, in Fig. 1 at 29, in which the segments 30 and 31 are in the electric circuit with the controller 32 in the car, and with a switch arm 33 bridging the same and operable by suitable links 34, 35 from the power-operating mechanism. In Fig. 2 we have shown the same diagrammatically, in which 36 indicates any suitable device for raising and lowering the elevator, such as a motor. 29 is a switch on one of the floors, and 37 is another similar switch at another floor operated by the door mechanism on that floor. It will be obvious that when either door is open, its switch is open and the car cannot be started, but as the door closes, the switch arm 33 is thrown to close the circuit. In Figs. 6 and 7 we have shown a modification of such a switch, in which the stationary contact plates 38 and 39 are in the electric circuit and are connected by a bridge contact 40 carried on a vertically movable spring-pressed rod 41. The rod has an adjustable toe 42, which is engaged and elevated by a roller 43 when the door is opened and which causes the terminals of the bridge contact 40 to pass over onto the dead seg-

ments 44 and 45, thus breaking the circuits as in the other illustrations.

It will be obvious that by the safety-lock arrangement, previously described, the operator may start the car from the floor without waiting for the complete closing of the door, because the door cannot be opened even though it were slightly ajar and with the toggle somewhat broken. The cushioning effect of the dash-pot is to cause the door to move somewhat slowly as it approaches the closed position, and as the operator may safely start his car before waiting for the complete closure, a material amount of time is saved which would otherwise be lost. This is particularly important in the operation of high speed elevators. The value of such a construction will be evident to any person familiar with the practical needs of high speed elevator service. It is particularly effective when used in connection with automatically closing doors. With such doors the operator of the car need only close the door as far as the safety point, and may then leave the floor with the car. The automatic closing device then completes the closing of the door.

We are aware that our invention may be embodied in devices widely differing from those preferred embodiments shown in the drawings and without departing from the scope of the claims herein made. We therefore do not desire to be limited to the construction illustrated and described.

What we claim as new is:

1. An elevator car and mechanism for raising and lowering the same, a controller for said operating mechanism, a door, check mechanism for the door automatically operable at several points during the latter part of the door's closing movement to prevent an opening movement by force applied directly to the door, and mechanism automatically throwing said controller to car-startable position in advance of the closed position of the door, said controller and check mechanism being so arranged that the latter will at least operate at a plurality of points after said controller is thrown.

2. An elevator car and mechanism for raising and lowering the same including a motor, an electric switch controlling said motor, a door, check mechanism for the door automatically operating at several points during the latter part of the door's closing movement to prevent an opening movement by force applied directly to the door, and mechanism automatically throwing said switch to car-startable position in advance of the closed position of the door, said controlling switch and check mechanism being so arranged that the latter will at least operate at a plurality of points after said controlling switch is thrown.

3. An elevator car and mechanism for raising and lowering the same, a controller for said operating mechanism, a door, check mechanism for the door comprising a pawl and a surface engageable thereby, one freely movable across the other by the closing movement of the door, whereby said check mechanism automatically operates at several points during the latter part of the door's closing movement to prevent an opening movement by force applied directly to the door, said pawl being adapted to automatically move out of engageable checking relation to said surface when the door is completely closed, and mechanism automatically throwing said controller to car-startable position in advance of the closed position of the door, said controller and check mechanism being so arranged that the latter will at least operate at a plurality of points after said controller is thrown.
4. An elevator car and mechanism for raising and lowering the same, a controller for said operating mechanism, and at each of a plurality of floors a door, check mechanism for the door automatically operating at several points during the latter part of the door's closing movement to prevent an opening movement by force applied directly to the door, and mechanism automatically throwing said controller to car-startable position in advance of the closed position of the door, said controller and check mechanism being so arranged that the latter will at least operate at a plurality of points after said controller is thrown.
5. An elevator car and mechanism for raising and lowering the same, a controller for said operating mechanism, a door, check mechanism for the door automatically op-

erating at several points during the latter part of the door's closing movement to prevent an opening movement by force applied directly to the door, and mechanism moved by the door and positively connected with said controller and throwing said controller to car-startable position in advance of the closed position of the door, said controller and check mechanism being so arranged that the latter will at least operate at a plurality of points after said controller is thrown.

6. An elevator car and mechanism for raising and lowering the same, a controller for said operating mechanism, a door, check mechanism for the door automatically operating at several points during the latter part of the door's closing movement to prevent an opening movement by force applied directly to the door, a toggle one member of which is connected to the door and the other to a relatively movable part, and mechanism operated by said toggle and automatically throwing said controller to car-startable position in advance of the closed position of the door, said controller and check mechanism being so arranged that the latter will at least operate at a plurality of points after said controller is thrown.
